UNITED STATES PATENT OFFICE.

FRANZ KNOPFE, OF CHEMNITZ, GERMANY.

SCAFFOLDING.

SPECIFICATION forming part of Letters Patent No. 650,900, dated June 5, 1900.

Application filed July 5, 1898. Renewed January 2, 1900. Serial No. 168. (No model.)

To all whom it may concern:

Be it known that I, FRANZ KNOPFE, a citizen of the United States, and a resident of Chemnitz-Beckenbürcke, in the Kingdom of 5 Saxony, Germany, have invented certain new and useful Improvements in Portable Scaffolding, of which the following is a specification, reference being had to the accompanying drawings, forming a part thereof, in which 10 similar letters and figures of reference indicate corresponding parts.

This invention relates to improvements in portable scaffolding, the object of the invention being to provide a structure of this character containing simple and interchangeable parts adapted to be quickly and accurately assembled, whereby a substantial structure of any desired dimensions may be produced. The structure is of such a nature that the 20 strain is equally distributed, and by its use danger of accidental collapse is entirely obviated, while at the same time the parts may be readily disassembled when desired for the purpose of transportation.

25 The invention will be hereinafter fully described, and specifically set forth in the annexed claims.

In the accompanying drawings, forming part of this specification, Figure 1 is a side 30 elevation of a section of my improved scaffolding. Fig. 2 is an end elevation thereof. Fig. 3 is a side elevation of a metallic coupling forming part of the scaffolding. Fig. 4 is a longitudinal sectional elevation thereof. 35 Fig. 5 is a plan view of the said coupling. Fig. 6 is a detail sectional elevation of a portion of the coupling, taken on a line $x-x$ of Fig. 5; and Fig. 7 is a vertical sectional elevation of a socket forming part of my structure.

40 In the practice of my invention I provide, primarily, longitudinal beams A, arranged parallel with each other to form a base or foundation for the scaffold. Upon this base I place the sockets B, which said sockets are 45 provided with flanges b for engagement with bolts b', adapted for fastening the sockets to the base-beams A. These said beams rest upon the ground, and for the purpose of adjusting them into horizontal position upon 50 uneven surfaces shoes C are secured to bolts c and pass through threaded collars c', formed in the ends of the beams, as illustrated in Fig.

1 of the drawings, whereby the act of turning the bolt c will raise or lower the shoes C to conform with the surface upon which the scaffold is to be built. The sockets B are further provided with laterally-extended lugs or projections b², containing apertures b³ for receiving the ends of the cross-braces D, forming part of the structure, which said braces are 60 secured by means of nuts d. In further carrying out my invention I employ a series of metallic couplings E. These said couplings are respectively supplied with platforms e, located horizontally and to one side of the 65 center. They are further provided with extended recesses e' for receiving beams or joists 1, forming part of the scaffold. These recesses are extended opposite to each other in alignment with the central opening, and a further 70 series of recesses e² are extended at right angles thereto for the purpose of receiving cross-beams 2.

Angular extensions e³ are formed between the central openings and the recesses e' for 75 the purpose of receiving cross-braces D', which said braces engage openings e⁴ and are secured by means of nuts e⁵. The couplings are further provided with extended lugs e⁶, with apertures e⁷ therein for engaging the 80 cross-braces D, which are secured by means of the nuts d. These said braces may comprise, if desired, two sections d' and d², connected to each other by means of turnbuckles d³, whereby the braces may be stiffened, if desired. 85

The invention further comprises vertical columns F, comprising sections f and f', arranged parallel and in staggered relation to each other, their adjacent ends engaging with 90 platforms e of the couplings E, the column F passing entirely through the vertical opening of the said coupling, whereby a strong and continuous column may be built up to any desired height. In building these columns a 95 section f is placed within a socket B and extended upwardly through one of the couplings E, the center thereof engaging the inner edge of the platform e. A section f' is then placed within the socket, its upper end resting beneath the platform e. Another coupling is then placed in reverse position, its platform resting on the upper end of the section f, and a further section f' is then placed 100

upon the platform *e* of the lower coupling and passed through the upper coupling. This operation is continued until the column reaches the desired height, and any number of columns may be employed, depending upon the dimensions of the scaffold required, the couplings all being connected to each other and to the sockets by means of the cross-braces *D* and *D'*, as shown in the drawings.

10 It is obvious that a structure built in this way will be very durable, and it being braced in all directions causes an equalization of the strain thereon, whereby all danger of accident by collapse is obviated.

15 Having thus described my invention, what I claim as new, and desire to secure by Letters Patent, is—

1. A scaffolding comprising a series of sockets mounted upon a movable base, and a series of sectional columns resting in said sockets, said columns comprising vertical sections arranged in staggered relation to each other, and a series of couplings surrounding the said columns and cross-braces connecting the 25 couplings with each other and to the sockets, substantially as shown and described.

2. In a scaffolding, the combination of a series of sockets having lugs projected therefrom and a series of couplings having platforms located therein, and a series of sectional columns engaging said platforms, the said couplings having recesses projecting therefrom, and also apertured lugs, the apertured lugs engaging cross-braces, and the recesses engaging hori-

zontally and laterally extended beams, substantially as shown and described. 35

3. In combination with a scaffolding comprising sectional columns, a series of couplings engaging said columns, the said couplings having platforms therein for engaging adjacent ends of the said sectional columns and also having recesses projected therefrom engaging lateral and longitudinal beams, and apertured projections engaging cross-braces, and a series of sockets secured to a portable 45 base, the said sockets connected with the said couplings by means of cross-braces, substantially as shown and described.

4. A scaffolding comprising a series of sockets mounted upon a movable base, said base 50 having vertically-adjustable shoes connected thereto for the purpose of leveling, and a series of sectional columns resting in said sockets, these columns comprising vertical sections arranged in staggered relation to each other, 55 and a series of couplings surrounding said columns, and diagonal cross-braces connecting the couplings with each other and to the sockets; the several parts of the scaffolding being interchangeable, substantially as 60 shown and described.

In testimony that I claim the foregoing as my invention I have signed my name, in presence of two witnesses, this 2d day of June, 1898.

FRANZ KNOOPFE.
